UNITED STATES PATENT OFFICE.

THOMAS J. SYLVESTER, OF PHILADELPHIA, PENNSYLVANIA.

GAME.

1,418,214.

Specification of Letters Patent. Patented May 30, 1922.

Application filed May 28, 1921. Serial No. 473,296.

To all whom it may concern:

Be it known that I, THOMAS J. SYLVESTER, a citizen of the United States, residing at Philadelphia, in the county of Philadelphia and State of Pennsylvania, have invented new and useful Improvements in a Game, of which the following is a specification.

The object of the present invention is to produce an interesting and instructive game designed to be played by two or more persons each representing a principal political body, and wherein a sphere arranged in a circular runway is caused, on manipulation of the device by the operator or player to enter radially arranged pockets which communicate with the runway, opposite each of said pockets being imprinted the names of the States comprising the United States and the electoral vote to which each State is entitled, the player causing the sphere to enter the pockets having the most electoral votes winning the election, or rather the contest.

A further object is to produce a game or toy comprising a board which is preferably in the nature of a flat disk or circular member, having, adjacent to its periphery a continuous runway, and the said board being formed with radially disposed depressions providing pockets that communicate with the runway, the center of the board being ornamented with a historical or geographical emblem, or both, the board, opposite the pockets having imprinted thereon the names of the States constituting the United States and the electoral vote to which each State is entitled, the said States being divided into the Middle Atlantic States, Rocky Mountain or Pacific States, the Central States, and the Southern States, a sphere being arranged in the runway and designed to be caused to enter the several pockets whereby two or more players representing the principal political parties may play at election, the figures designating the electoral votes of the several States, the manner in which the States are divided into sections, the emblematic ornamentations on the board affording appropriate educational matter, while the playing of the game excites both interest and amusement.

The drawings illustrate a satisfactory embodiment of the improvement, and wherein:

Figure 1 is a plan view of the same.

Figure 2 is a transverse sectional view through the improvement.

As disclosed by the drawings, I make use of a flat board 1, which, however, is circular in plan. The board, adjacent to the periphery thereof is provided with a continuous runway 2 for a sphere (not shown). Inward of the runway, but communicating therewith, there are radially disposed depressions forming pockets 3. Opposite each pocket, the board has imprinted thereon the names of the several States in the Union and figures indicating the electoral votes of each of said States. In the center of the board there is imprinted an historical or geographical emblem. In the present instance, I have illustrated a picture of Mt. Vernon, the former home and final resting place of the first President, and therebelow a facial resemblance of the first President of the United States. These impressions are surrounded by a broken circle which is indicated by the numeral 4, the said circle, at the ends thereof, having arrows 5 pointing in the direction of certain of the States opposite certain of the pockets. In the circle provided by the broken curved lines 4, and between the arrows at the ends of the said broken lines, I have imprinted "Southern States," which are arranged opposite the States in the southern portion of our country, between the arrows representing the Middle States, the words "Middle States," between the arrows pointing to the New England States, the words "New England States," between the arrows opposite the Rocky Mountains, or the Pacific States, the words "Rocky Mountain or Pacific States," and between the arrows opposite the Central States, the words "Central States." The data thus imprinted on the board affords appropriate educational matter to the players of the game. The sphere is placed in the runway 2 and is propelled therearound. The board is tilted by the player in an attempt to have the sphere enter certain pockets which represent certain desirable States to be gained by the player who represents one of the principal political parties. Each player is entitled to a certain amount of goes, and the player who causes the ball to enter the pockets that represent a majority of the States, wins the electoral contest or game.

Having described the invention, I claim:

1. A toy or game, as herein described, comprising a board having a circular depression providing a runway for a sphere, said board having radial depressions forming pockets

which communicate with the runway and into which the sphere is designed to be guided, said board having imprinted thereon opposite each pocket the name of the several States constituting the United States and figures representing the electoral votes of the several States.

2. In a toy or game, as herein described, a board having a circular depression providing a runway for a sphere and radial depressions providing pockets which communicate with the runway, said board, opposite each pocket having imprinted the name of a State thereon, and the number of pockets corresponding to the number of States in the Union, said board having further imprinted thereon the numbers indicating the electoral vote of the several States, and the names of the States being grouped to represent a division of said States.

3. In a toy or game, as herein described, a board having a circular depression providing a runway for a sphere and radial depressions providing pockets which communicate with the runway, said board, opposite each pocket having imprinted the name of a State thereon, and the number of pockets corresponding to the number of States in the Union, said board having further imprinted thereon the numbers indicating the electoral vote of the several States, and the names of the States being grouped to represent a division of said States, said board having imprinted thereon a broken circle whose ends terminate in arrows directed toward the divisions of the States and having imprinted in the broken circle historical or geographical emblems.

In testimony whereof I affix my signature.

THOMAS J. SYLVESTER.
